UNITED STATES PATENT OFFICE

156,946

FRUIT RECEPTACLE OR SIMILAR ARTICLE

Thomas Farrell, Chicago, Ill., assignor to Starr Productions, Chicago, Ill., a partnership composed of Richard Starr, Thomas Farrell, and Frank G. Stein

Application May 18, 1948, Serial No. 146,434

Term of patent 3½ years

(Cl. D44—10)

To all whom it may concern:

Be it known that I, Thomas Farrell, a citizen of the United States of America, residing at Chicago in the county of Cook, State of Illinois, have invented a new, original, and ornamental Design for a Fruit Receptacle or Similar Article, of which the following is a specification, reference being made to the accompanying drawings, forming part thereof.

Referring to the drawings, Fig. 1 is a side view of a fruit receptacle or similar article embodying my new design; Fig. 2 is a front view; Fig. 3 is a rear view, and Fig. 4 a top plan view of the same.

I claim:

The ornamental design for a fruit receptacle or similar article, substantially as shown.

THOMAS FARRELL.
